UNITED STATES PATENT OFFICE

LINDEN A. THATCHER, OF BELLEVILLE, NEW JERSEY, ASSIGNOR TO UNDERWOOD
ELLIOTT FISHER COMPANY, OF NEW YORK, N. Y., A CORPORATION OF DELAWARE

STENCILING MACHINE

Application filed February 19, 1929. Serial No. 341,234.

This invention relates to duplicating machines where a foraminous stenciling cylinder may co-operate with a feed-roller to produce stencil copies, and more particularly 5 to an improved mechanism applying a coat of ink to the interior surface of the cylinder when required.

The main object is to provide an inking device which is simple, convenient, efficient 10 and clean in operation. The invention includes means whereby to cause an ink-fountain to discharge ink and simultaneously to press an ink-spreader or brush against the surface being inked.

15 There is secured within the usual perforated stenciling cylinder an ink-fountain or container which may assume the form of a drum extending from end to end of the stenciling cylinder. This container or fountain- 20 drum may be rotatively shifted or swiveled, at will, independently of the rotation of the stenciling cylinder, so as to allow the ink to drop or trickle through suitable apertures provided in the container, onto the interior 25 surface of the stenciling cylinder. The ink filters through the perforations of the stencil-cylinder and permeates the usual ink-blanket, which may be stretched around the cylinder to form the backing for a stencil-sheet to be 30 fastened thereon.

An ink-spreader or brush, which may also extend from end to end of the stenciling cylinder, is movable between operative and inoperative position, that is, to and from said 35 surface of the stencil-cylinder. The movement of the brush is coupled with the movement of said ink-fountain, and when the latter is held in ink-discharging position, the brush is pressed against the wall of the stenciling cylinder, so that now by giving the latter several turns, the ink may be evenly distributed. After sufficient ink has been applied, the ink-fountain will be allowed to return to inoperative position, together with 40 45 the distributor-brush.

The novel inking device is shown with a duplicating or stenciling machine, such as shown in my co-pending application No. 334,157 dated January 22, 1929, the inking device to be entirely enclosed by the stenciling cylinder to prevent ink leakage at inopportune places, such as is liable to render the operator loath to the use of the machine. The enclosure is also well apt to subdue undesirable evaporation or drying of the ink 50 and thus to keep the machine longer in good working condition.

The stenciling cylinder is supported in end journals upon a machine-frame, and the ink-fountain is supported coaxially with the stenciling cylinder. An ink-inlet port in the form of a hollow shaft or pipe is provided at one end of the ink-fountain extending centrally through the adjacent journal. A suitable extension of said hollow shaft may 55 form a handle to be rigid with the ink-container, by means of which the latter may be conveniently operated.

The brush is preferably suspended directly from the ends of the ink-fountain. 60 When the latter is rotatively shifted to discharge ink, the brush or spreader, due to its eccentric mounting, will approach the inking surface. By means of a toggle linkage provided between the free end of 65 the spreader and the machine-frame, the spreader is efficiently guided into and out of use, in accordance with the shifting of the ink-fountain.

The operator's hand, in positioning the 80 ink-fountain discharge, also presses the brush effectively against the inking surface. In this way the brush, despite its possibly worn condition, can always be caused to work efficiently upon the surface. Especially 85 when after a period of idleness the ink-blanket has become dry and the ink sluggish, the brisk stir of the bristles, acting through the perforations upon the blanket, is extremely desirable for retrieving the blanket 90

quickly and for reviving the filtering of the ink.

Another feature provides simple and efficient means for automatically closing and opening said ink-discharging apertures of the ink-container. Novel closure members are designed to effectively seal said apertures and to prevent the same from getting clogged up with dried ink.

According to still another feature, an ink-distributor substantially as described is rendered active in a convenient manner by the depression of a handle against the tension of a returning spring.

Other features and advantages will hereinafter appear.

In the accompanying drawings,

Figure 1 is a longitudinal section through the stenciling cylinder, and shows the novel 20 inking device enclosed therein as in idle position.

Figure 2 is a perspective view to supplement Figure 1.

Figure 3 is a cross-sectional view showing 25 the inking device as in idle position.

Figure 4 is a similar view; however, showing the inking device in action with the ink dropping from the ink-container, the brush being engaged upon the inking surface, and 30 the stenciling cylinder being in motion, causing the brush to spread the ink.

Figure 5 shows a detail of the resiliently-mounted valve-bodies.

A stencil-cylinder 10 having the usual per- 35 forations 11, and carrying an ink-blanket 12 and a stencil-sheet (not shown), has closed ends including a hub 13 and a hub 14, the latter forming part of a detachable end plate 15, which is secured by screws 16 to the cyl- 40 inder-body. The stenciling cylinder is sup- ported in bearings 16^a and 17 of the main machine-frame and shown to co-operate with a feed-roll 17^a, (dot and dash) Figure 3, for producing stencil-copies, said bearings hav- 45 ing removable covers 18 allowing for con- venient detachment of the stenciling cylinder from the machine. At one end, the cylinder is supported by means of a stub-shaft 19 fixed in the hub 14 by a stud 20 lodging in a 50 recess 21 of said hub 14, and carrying at its free end a crank 22. The other end of the cylinder 10 is supported upon a bearing sleeve 23 rigidly fixed within the main bearing 17 by means of a key-and-groove connec- 55 tion 24. The stenciling cylinder thus is ro- tatable independently from the novel inking device, which is entirely enclosed within the stenciling cylinder.

The device includes a cylindrical ink foun- 60 tain or container rotatable, at will, coaxially with the stenciling cylinder. The cylinder has an end plate 25 into which is shown to be threaded a shoulder-pivot 26 to fit centrally into a bore of the above-mentioned stub- 65 shaft 19. Centrally extending from the

other end plate 26^a of the container is a pipe 27 supported within said rigid sleeve 23 for rotation, and conveniently serving as an inlet for supplying ink to the container. The inlet is supplemented by an elbow fitting 28, a vertical pipe 29 and a screw-cap 30 serving as a closure piece and equally as a handle for the operation of the inking device, as will be presently seen.

By using the inlet-pipe and the cap 30 as a handle, the cylindrical ink-container may be given a fraction of a full turn, as indicated in Figure 4, just enough to allow the ink to drop through openings 31 suitably disposed

in the wall of the container, there being also shown a vent-pipe 32 upon the container which should be of sufficient length to prevent ink from flowing out through the vent when the container is well filled up with ink (as shown).

As the ink trickles upon the interior surface of the stenciling cylinder, a brush 33 extending from end to end thereof will be brought to bear upon the inking sur-

face while simultaneously the stenciling cylinder may be given a couple of turns, so 90 as to cause the brush to evenly distribute the discharging ink over the whole cylinder. The brush, by means of a set-screw 34, may be

fixed in a socket or channel 35 of sheet-metal, which, by means of arms 36 and 37, is endwise suspended from a shaft 38, which in turn is

journaled in the end plates 25 and 26^a of the ink-container, said arms being rigidly fas- 95 tened by means of pins 39 upon said shaft 38.

As the ink-container is rotated from its in- 100 operative position, Figure 3, to its ink-dis- charging position, see Figure 4, the brush, by reason of its eccentric pivotal mounting, will

tend to swing toward the surface of the sten- 105 ciling cylinder, and is moreover urged to do so, that is to bear against the inking surface, through the bracing action of a toggle-link 110

39^a pivoted at 40 upon the brush-arm 37, and at 41 upon a rigid arm 42 extending from the

above-mentioned rigid bearing sleeve 23. 115 While this toggle-link constitutes a simple, rugged and efficient connection for operating the brush, other suitable means may be em- 120 ployed to control said brush. The handle of the inking device is operated against the ten- sion of a coil-spring 43, anchored in an ear 125 44 bent over from the one end plate 25, and is attached to a pin 45 shown upon the brush-arm 37. Upon releasing the handle, there-

fore, said spring 43 will restore the ink-con- tainer as well as the brush to inoperative 130 position, Figure 3. To perform a double task, the spring 43 in its Figure 3 condition is

shown to be slightly flexed between its anchoring points to fit tangentially into a circu- 135 lar groove 43^a upon the stub-shaft 19, so as to incidentally detain the same in place upon the pivot 26 whenever the stencil-cylinder, together with the enclosed inking device, hap- 140 pens to be lifted off its bearings 16^a and 17. 145

It will be furthermore seen that the actual pressure of the operator's hand, see Figure 4, will urge the brush against the inking surface to secure effective distribution of the ink. While the inking device may be easily removed and inspected, owing to the removable cylindrical end 15, it is otherwise entirely enclosed, precluding any possibility of ink escaping from the inside of the cylinder at 10 inopportune places and smudging the hands of the operator.

It is an essential refinement to provide means for automatically opening and closing the ink-discharging apertures when the inking device is operated, the purpose being, 15 firstly to prevent the liquid as far as possible from evaporating, and secondly to keep said apertures 31 clear, that is, free from dried-up ink which is liable to clog up these openings, and thereby to cause trouble in operation. To this end, simple and efficient means are provided in the form of a plate 46, preferably of resilient sheet metal, to be fastened as by screws 47 upon the shaft 38, and 20 extending from end to end thereof. The plate is sub-divided into a number of resilient tongues 48 according to the number of apertures 31, each tongue carrying loosely anchored therein a conical valve-like body or 25 plug 49 shaped to properly close up said apertures 31, as may be clearly seen from Figure 3 and detail Figure 5. When the plugs operate to close the apertures, the point of the plug-cone will find its way into the opening, 30 and due to its flexible anchorage, the plug will properly adjust itself upon its seat. The wedging action of the cones within their seats will help to prevent ink from settling down upon said seats. While the inking device is 35 working, as in Figure 4, the plugs are swung away from their seats together with the brush-arms 36 and 37 and allow the ink to discharge unhindered through the openings, as shown.

45 Variations may be resorted to within the scope of the invention, and portions of the improvements may be used without others.

Having thus described my invention, I claim:

50 1. In a duplicating machine, the combination with a stencil-carrier, of an ink-distributor including an ink-container operable to discharge ink onto the stencil-carrier, an ink-spreader normally idle but operable to bear upon the stencil-carrier when ink is to be applied thereto while said stencil-carrier is to be moved relatively to the spreader for the purpose of spreading the ink, and means 55 for coupling the operation of the ink-container with the operation of the ink-spreader.

55 2. In a duplicating machine, the combination with a foraminated cylindrical stencil-carrier rotatably supported in the machine-frame, of an ink-distributor arranged with 60 in said stencil-carrier and including an ink-

70 container extending from end to end of said stencil-carrier and operable in order to discharge ink onto the interior surface of the stencil-carrier, an ink-spreader also extending normally idle from end to end of said stencil-carrier, but operable to bear upon said interior surface when ink is to be applied thereto while said stencil-carrier is to be rotated for the purpose of spreading the ink, and means for coupling the operation of the 75 ink-container with the operation of the ink-spreader.

75 3. In a duplicating machine, the combination with a foraminated cylindrical stencil-carrier rotatably supported in the machine-frame, of an ink-distributor located within 80 said stencil-carrier and including an ink-container normally stationary but rotatively shiftable to discharge ink onto the interior surface of said stencil-carrier, an ink-spreader normally idle but operable to bear upon the interior surface of said stencil-carrier when ink is to be applied thereto, said spreader to be suspended from said container and eccentrically of the cylinder-axis for 85 swinging movement to and from the inking surface as said container is shifted, said stencil-carrier to be rotated for the purpose of spreading the ink when the spreader is engaged upon the surface, and means for positively guiding the free end of said spreader 90 between operative and idle position in unison with the respective shift-positions of said container.

95 4. In a duplicating machine, the combination with a foraminated cylindrical stencil-carrier rotatably supported in a machine-frame, of an ink-distributor located within 100 said stencil-carrier and including an ink-container normally stationary but rotatively shiftable to discharge ink onto the interior surface of said stencil-carrier, an ink-spreader normally idle but operable to bear upon the interior surface of the stencil-carrier when ink is to be applied thereto, said spreader to be suspended from said container and eccentrically of the cylinder-axis 105 for swinging movement to and from the cylinder-surface as said container is shifted, said stencil-carrier to be rotated for the purpose 110 of spreading the ink when the spreader is engaged upon the surface, and a toggle-link between the free end of the movable spreader and a point rigid with the machine-frame, said link to render positive the movement of 115 said spreader between idle and operative position in unison with the respective shift-positions of the ink-container.

120 5. In a duplicating machine, the combination with a foraminated cylindrical stencil-carrier rotatably supported in the machine-frame, of means for dispensing ink onto the interior surface of the cylinder, an ink-spreader extending from end to end of said stencil-carrier, said spreader normally idle 125

and spaced from the interior surface of the cylinder but operable to bear against the surface in order to spread ink applied thereto while the stencil-carrier is to be rotated, 5 and a toggle-device backed upon a portion rigid with the machine-frame, for controlling the movement of the ink-spreader to and from the surface to be inked.

6. In a duplicating machine, the combination 10 with a foraminated cylindrical stencil-carrier having ends to form a closed drum, one end to be detachable for gaining access to the interior of the drum, said drum rotatably supported by journals upon the machine-frame, of a closed ink-reservoir substantially as herein disclosed, said ink-reservoir entirely enclosed within said drum, and accessible means extending centrally through a journal into the drum, and movable within 15 said journal to effect discharge of ink from said reservoir within the drum.

7. In a duplicating machine, the combination 20 with a foraminated cylindrical stencil-carrier rotatably supported by end journals upon the machine-frame, of an ink-distributor 25 within said stencil-carrier, including an ink-container extending from end to end of the stencil-carrier, means for independently operating the ink-container, so as to discharge ink, at will, onto the interior surface 30 of the stencil-carrier, said ink-container having at one end an axial tubular extension rigid therewith and leading centrally through the adjacent journal, so as to serve 35 as a convenient ink-inlet port for the container.

8. In a duplicating machine, the combination 40 with a foraminated stencil-cylinder rotatably supported by end journals upon the machine, of an ink-distributor within said stencil-cylinder, including an ink-container 45 extending from end to end of the stencil-cylinder and mounted coaxially therewith for independent rotative shifting, to discharge ink on the interior surface of the stencil-cylinder, said ink-container having suitable ink-discharging apertures and having at one end 50 an axial tubular extension rigid therewith and leading centrally through the adjacent journal, so as to serve conveniently as an ink-inlet port for the container and equally as a handle by means of which to operate said container at will.

9. In a duplicating machine, the combination 55 with a rotatable stencil-cylinder, of an ink-distributor located within said stencil-cylinder and including an ink-container longitudinally extending from end to end of the stencil-cylinder and having a longitudinal 60 array of apertures for discharging the ink, said container to be rotatively shiftable between operative and inoperative position, plugs fitted to enter said apertures and to close the same when the container is inoperative, and means for controlling said plugs in

accordance with the respective shift-positions of said container.

10. In a duplicating machine, the combination 70 with a rotatable stencil-cylinder, of an ink-distributor located within said stencil-cylinder and including an ink-container longitudinally extending from end to end of said stencil-cylinder and having a longitudinal array of apertures for discharging the ink, 75 said container to be rotatively shiftable between operative and inoperative position, plugs in the form of cones, fitted to enter and close said apertures when seated upon conforming faces while the container is inoperative, and means for controlling said plugs in accordance with the respective positions of said fountain.

11. In a duplicating machine, the combination 80 with a rotatable stencil-cylinder, of an ink-distributor located within said stencil-cylinder and including an ink-container longitudinally extending from end to end of said stencil-cylinder and having a longitudinal array of apertures for discharging the ink, 85 said container to be rotatively shiftable between operative and inoperative position, plugs fitted to enter and close said apertures when the container is inoperative, means for controlling said plugs in accordance with the respective shift-positions of the container, 90 and means for resiliently supporting said plugs, insuring their true seating.

12. In a duplicating machine, the combination 95 with a rotatable stencil-cylinder, of an ink-distributor located within said stencil-cylinder and including an ink-container longitudinally extending from end to end of said stencil-cylinder and having a longitudinal array of apertures for discharging the ink, 100 said container rotatively shiftable between operative and inoperative position, plugs fitted to enter and close said apertures when the container is inoperative, and means for controlling said plugs in accordance with the respective shift-positions of the container, 105 said means including a resilient tongue for each plug to carry the same for true seating.

13. In a duplicating machine, the combination 110 with a rotatable stencil-cylinder, of an ink-distributor located within said stencil-cylinder and including an ink-container longitudinally extending from end to end of said stencil-cylinder and having a longitudinal array of apertures for discharging the ink, 115 said container to be rotatively shiftable between operative and inoperative position, means controlled in accordance with the shift-positions of the container for opening and closing respectively said apertures and including plugs fitted to enter and close said apertures, 120 and a resilient finger for each plug, said plugs to be loosely anchored upon said fingers for true seating when urged to close said apertures.

14. In a duplicating machine, the com- 125

5 bination with a rotatable stencil-cylinder, of an ink-distributor located within said stencil-cylinder and including an ink-container longitudinally extending from end to end of the stencil-cylinder, said container to be rotatively shiftable between operative and inoperative position and having a longitudinal array of ink-discharging apertures, an ink-spreader also extending from end to end of the stencil-cylinder and to be suspended from the ends of said container for swinging movement to and from the inking surface, and means including a closure-member for said apertures, said closure-member swingable together with said spreader, so that retreat of the spreader will close said apertures, while the advance of the spreader will open the same.

10 15. In a duplicating machine, the combination with a rotatable stencil-cylinder, of an ink-distributor located within said stencil-cylinder and including an ink-container operable for discharging ink onto the interior surface of said cylinder, an ink-spreader operable to bear upon said interior surface, and spring-means for returning the operating elements of said ink-distributor to ineffective position.

20 25 30 35 40 45 50 55 60 65 16. In a duplicating machine, the combination with a rotatable stencil-cylinder, of an ink-distributor located within said stencil-cylinder and including an ink-container extending from end to end of said stencil-cylinder and rotatively shiftable for discharging ink onto the interior surface of said cylinder, an ink-spreader also extending from end to end of said cylinder, said spreader endwise suspended from said container to be pivoted thereon for swinging movement to and from the cylinder-surface, a spring tensioned to interconnect said spreader with said container and effective to normally hold said spreader remote from said cylinder-surface and hugged against said container, means for shifting said container in order to discharge ink, and toggle-linkage backed upon a point rigid with the machine-frame, for simultaneously urging said spreader away from said container and toward the cylinder-surface, said spring-tension effective upon release of said shifting means to return the spreader as well as the container to ineffective position.

70 75 80 85 90 95 100 105 110 115 120 125 130 17. In a duplicating machine, the combination with a foraminated cylindrical stencil-carrier rotatably supported by end journal-bearings upon the machine, of an ink-distributor within said stencil-carrier, both stencil-carrier and ink-distributor to be liftable as a unit from said bearings, said ink-distributor including an ink-container extending from end to end of said stencil-carrier and mounted coaxially therewith for independent rotative shifting to discharge ink onto the interior surface of the stencil-carrier,

there being a stub-shaft rotatable in one bearing and which is to support thereon one end of said stencil-carrier and which has means for impelling the latter, said stub-shaft also carrying at its inner end the adjacent end of the coaxial ink-container, an ink-spreader also extending from end to end of said carrier, said spreader endwise suspended from said container to be pivoted thereon for swinging movement to and from the interior surface of the stencil-carrier, a coil-spring tensioned between the container and the free end of said spreader adjacent said stub-shaft and effective to normally hold said spreader remote from said surface and hugged against the container, said spring in performing a double task arranged to fit tangentially into a groove upon said adjacent stub-shaft, so as to detain the same from axial displacement when the stencil-carrier together with the ink-distributor is removed from its bearings upon the machine, means for rotatively shifting said container against said spring-tension in order to discharge ink, and a toggle-linkage backed upon a point rigid with the machine-frame for pressing the spreader against the interior surface of the carrier while the container discharges ink, said spring-tension effective upon release of said shifting means to return the spreader as well as the container to ineffective position.

18. In a duplicating machine, the combination with a foraminated cylindrical stencil-carrier, of an ink-distributor within said stencil-carrier, and means for supporting both said stencil-carrier and said ink-distributor upon the machine-frame, said ink-distributor including an ink-container extending from end to end of said stencil-carrier and mounted coaxially therewith for independent rotative shifting to discharge ink onto the interior surface of said stencil-carrier, said supporting means including a stub-shaft rotatable in a journal-bearing upon the machine-frame and which is to support thereon one end of said stencil-carrier and which has means for impelling the latter, said stub-shaft also serving as a bearing for the adjacent end of the coaxial ink-container, said supporting means further including a sleeve rigid upon the machine-frame to support thereon the other end of the stencil-carrier and also to serve as a journal-bearing for the corresponding end of the independently-shiftable ink-container.

19. In a rotatable cylindrical stencil-carrier, an ink-reservoir mounted therein having valves to control the discharge of ink therefrom, a movable ink-distributor normally out of engagement with the carrier, and means, effective in a single movement, to operate said valves to discharge the ink and also move the distributor against the inside of the carrier for spreading the ink when the carrier is rotated.

20. In a duplicating machine, the combination with a stencil-carrier, of an ink-reservoir operable to discharge ink on the carrier, an ink-spreader movable into effective and ineffective positions with reference to the carrier, the spreader being operable to bear against the carrier to spread the discharged ink thereon when the carrier is moved relatively thereto, and a single means 5 co-ordinating the operations of the reservoir and the spreader.
